INVENTOR:
William H. Nunamacher,
By
Russell W. Everett,
ATTORNEY.

UNITED STATES PATENT OFFICE.

WILLIAM H. NUNAMACHER, OF NEWARK, NEW JERSEY.

JOURNAL-BEARING FOR RAILWAY-CARS AND THE LIKE.

1,281,817.

Specification of Letters Patent Patented Oct. 15, 1918.

Application filed June 3, 1918. Serial No. 286,897.

To all whom it may concern:

Be it known that I, WILLIAM H. NUNAMACHER, a citizen of the United States, and a resident of Newark, in the county of Essex 5 and State of New Jersey, have invented new and useful Improvements in Journal-Bearings for Railway-Cars and the like, of which the following is a specification.

The objects of this invention are to enable 10 roller bearings to be applied to the trucks of railway cars and the like for receiving the axles of the wheels; to enable the rollers to be readily accessible for removal or replacement; to secure a simple and durable 15 construction, which can be applied to railway trucks now in use, and to obtain other advantages and results as may be brought out in the following description.

Referring to the accompanying drawing, 20 in which like numerals of reference indicate the same parts throughout the several views,

Figure 1 is a side elevation of a portion of a car truck and wheel to which my invention has been applied;

Fig. 2 is a perspective view of the journal box removed from the truck;

Fig. 3 is an outer end view of the journal box on larger scale with the cover removed;

Fig. 4 is a cross-section of the journal box 30 through its rollers;

Fig. 5 is a detail view of one of the rollers;

Fig. 6 is a central vertical section taken longitudinally through the axle, and

Fig. 7 is an inner end view of the journal box.

In the specific embodiment of the invention shown in said drawings, 1 indicates a journal box of any suitable and well-known 40 type, such for example as the one of my prior Patent No. 1,074,811 issued October 7, 1913, said particular journal box being removably mounted in the car truck frame 2. More especially, the journal box is provided 45 on its outside and intermediate its inner and outer ends with a peripheral slideway 3 adapted to receive at the top and bottom of the journal box arms 4, 5 of the truck frame, and at one side a cross-piece 6 of the truck 50 frame, while the other side receives a removable filling block 7 which fits between the arms of the truck frame and is held by an upright bolt 8 passing through all three parts. Reference may be had to my said 55 prior patent for further details of the

mounting of the journal box in the truck frame, those features forming no part of the present invention and therefore requiring no further description here. My present invention can be used with any ordinary 60 and well-known type of journal box regardless of how it is mounted on the car truck.

10 indicates the cover for the outer end of the journal box, which is opened for inspection and oiling, said cover being hinged 65 at the top and closing against an upwardly curved extension 11 of the front end of the floor of the journal box.

Inside the journal box is a rectangular roller cage 12, which fits the box laterally 70 but in an up and down direction is considerably shorter than the height of the box. In use this cage 12 lies inside a depending stop 13 across the top of the journal box, and provides a space between itself and the bottom of the journal box for waste or other absorbent material for oil. Preferably the height of the cage is such that when lowered sufficiently to pass the stop 13 it can easily be removed from the journal box over the 80 front bottom extension 11. The cage 12 has a cylindrical opening 14 to hold an annular series of rollers 15 around the reduced end 16 of the axle 17, as clearly shown in the drawings. 85

Upon the opposite ends of the cage are retaining plates 18, 19, which have round openings of a little less diameter than the opening 14 of the cage, so as to project over the ends of the rollers and hold them 90 against endwise movement. The edges of these openings in the end plate are preferably rounded interiorly, as at 20, to better fit against the beveled or rounded ends of the rollers. In order to facilitate removal 95 or insertion of the rollers, the front end plate 18 is made sectional, with the ends of the removable section 21 beveled as at 22 or otherwise adapted to underlie the ends of the fixed section 23. 100

The shoulder formed by the reduced end 16 of the axle is concaved or rounded, as at 24, to fit against the rounded ends of the rollers, and the extremity of the axle receives an end bolt 25 with a threaded stem 26 to 105 screw into the axle and an outer angular portion 27 to receive a wrench for turning. The main portion 28 of the head of the bolt is large enough to overlie the ends of the rollers 15 but smaller than the opening 110

of the end plate 18, and preferably is concaved or rounded at its inner edge to fit against the rounded ends of the rollers as at 29.

5 In order to enable the rollers 15 to be oiled from the lubricating material in the lower part of the journal box, the bottom of the cage has openings which I have shown in the drawings provided by slotting transversely across the cage, as at 30, 30, so as to cut through into the opening or roller chamber 14. Any other suitable construction for obtaining this result might be employed, however.

10 15 In use the journal box rests upon the top of the roller case 12, back of the stop 13, and whenever it becomes necessary to inspect the rollers, the load is jacked up to raise the journal box away from the roller cage 12 sufficiently for the stop 13 to clear the top of the roller cage. Then the end bolt 25 can be removed and the upper section of the end plate 18, whereupon free access is had to the rollers 15. In order to accommodate this 20 upward movement of the journal box with respect to the axle, the aperture 31 in the inner end wall of the journal box is elongated vertically or made elliptical, as shown in Fig. 7.

25 30 My improved roller bearing can be used not only for freight cars on railways but also for passenger coaches, trolley car service, trucks or any kind of vehicles having journal bearings to which it can be adapted. Various 35 modifications and changes may be made in the course of such adaptation without departing from the spirit and scope of the invention, and I do not wish to be understood as restricting myself except as required by 40 the following claims when construed in the light of the prior art.

Having thus described the invention, what I claim is:

1. The combination with a journal box 45 and means for supporting the same, of a roller cage in said journal box having a limited movement vertically with respect thereto, an axle projecting into said roller cage, and rollers around said axle held by 50 said cage.

2. The combination with a journal box and means for supporting the same, of a roller cage in said journal box having a

limited movement vertically with respect thereto, an axle projecting into said roller 55 cage, rollers around said axle held by said cage, and means for preventing endwise movement of the axle with respect to said rollers.

3. The combination with a journal box 60 and means for supporting the same, of a roller cage in said journal box having a limited movement vertically with respect thereto, an axle projecting into said roller cage, rollers around said axle held by said 65 cage, and an end bolt screwed upon the end of the axle having a flange projecting over the ends of the rollers.

4. The combination with a journal box 70 and means for supporting the same, of a roller cage in said journal box having end plates with apertures smaller than the aperture of the cage, an axle projecting into said roller cage, and rollers between said axle and cage and held against endwise movement by 75 the said end plates.

5. The combination with a journal box and means for supporting the same, of a roller cage in said journal box having end plates with apertures smaller than the aperture of 80 the cage the outer end plate being sectional with one section adapted to underlie the other at their meeting edges and to be detachably secured at its opposite edge, an axle projecting into said roller cage, and rollers 85 between said axle and cage and held against endwise movement by the said end plates.

6. The combination with a journal box and means for supporting the same, said journal box having a stop at the upper part 90 of the outer end of its opening, a roller cage in said journal box adapted to engage said stop or be released therefrom by raising the journal box with respect to the cage, an axle projecting into said roller cage, and rollers 95 around said axle held by said cage.

7. The combination with a journal box having an upwardly projecting extension at the outer end of its bottom and a stop at the outer end of its top, of a roller cage in said 100 journal box normally engaging said top behind the stop and adapted when the box is raised with respect to the axle to pass outward between said stop and floor extension.

WILLIAM H. NUNAMACHER.
